ELECTRODE LEAD

Filed Aug. 18, 1926

Inventor:
William A. Ruggles
by *Wm. A. Ruggles*
His Attorney.

UNITED STATES PATENT OFFICE.

WILLIAM A. RUGGLES, OF SCHENECTADY, NEW YORK, ASSIGNOR TO GENERAL ELECTRIC COMPANY, A CORPORATION OF NEW YORK.

ELECTRODE LEAD.

Application filed August 18, 1926. Serial No. 130,032.

My present invention relates to electron discharge power tubes and more particularly to electrode leads adapted to carry relatively heavy currents.

- 5 In the ordinary form of power tube the grid lead is usually a small wire extending through a glass seal in the top or side of the tube and adapted to carry currents up to about 20 amperes. The lead is generally 10 welded to the grid support and provided with a few turns inside the tube in order to facilitate sealing of the tube. With a lead of this type a gas-tight seal is easily made and maintained, and the turns within the 15 tube have little effect on the operation of the tube owing to the comparatively low frequency currents employed. When the tube is employed in short wave transmission, however, a different situation arises in 20 view of the fact that the grid element may be required to carry a current of the magnitude of one hundred amperes at frequencies varying from ten million to thirty million cycles per second. In order to 25 carry currents of this magnitude the grid lead should be relatively large and it should preferably be straight in order to avoid the inductive effect resulting from the use of turns within the tube. If such a lead is 30 flexible it is not feasible to make a soldered connection with the grid or to make a gas-tight seal, while if it is solid, it is impossible to connect the lead directly to the grid, since the expansion of the lead due to the 35 heat developed in the tube is so great that the seal would quickly be broken and the vacuum in the tube destroyed.

It is one of the objects of my invention to provide a flexible connector between a grid 40 and a rigidly mounted lead, which is adapted to carry relatively heavy current without causing injury to the usual glass seal through which the lead extends.

The novel features which I believe to be 45 characteristic of my invention are set forth with particularity in the appended claims. The invention itself, however, will best be understood by reference to the following specification taken in connection with the 50 accompanying drawing in which Fig. 1 shows in elevation a 20 kw. tube which embodies the features of my invention; Fig. 2 is a perspective view of one form of grid lead comprising a flexible metallic strap de- 55 tachably connected to a grid support and a

rigidly mounted lead; while Fig. 3 is a perspective view of a modified form of my invention.

Referring to the drawing, I have indicated at 1 a power tube provided with the 60 usual anode 2, cathode and a grid or control element. The upper portion of the tube comprises a glass envelope 3 provided with a reentrant portion 4 through which the cathode leads 5 extend and an extension 6 65 having a reentrant portion including a seal or press 7 into which a solid tungsten lead 8 is sealed. A metallic grid supporting collar 9, which may be made of a nickel copper alloy such as Monel or any other suitable metal, is mounted on the reentrant portion 4 and provided with parallel flanges 10 whereby the collar may be secured in position.

The grid lead comprises a flexible strap 75 11 of annealed copper which extends substantially parallel to the outer surface of collar 9 and is provided with channels 12 at one end thereof adapted to engage the outer surfaces of the flanges 10 and to be detachably secured thereto as clearly indicated on the drawing. The opposite end of the flexible strap 11 is provided with a screw threaded extension 13 adapted to be engaged by a corresponding screw threaded 85 portion 14 on the rigid lead 8.

When the grid or control element of the tube carries a heavy current the amount of heat developed in the tube is very large and as a result strap 11 tends to expand. The 90 expansion of the strap takes place between the ends thereof and in a radial direction with respect to the collar 9. As a result when the tube is in operation there is no tendency to destroy the vacuum tight seal 95 7 maintained between the rigid lead 8 and the reentrant portion of the extension 6.

In Fig. 3 a modified form of my invention is shown, which is especially adapted for use with larger currents than the form 100 shown in Figs. 1 and 2. In this case it will be found desirable to employ a heavier strap than that shown in Fig. 2. In such an event strap 11 is merely made longer to provide sufficient flexibility. This is accomplished by turning the strap in the opposite direction from that shown in Fig. 2.

What I claim as new and desire to secure by Letters Patent of the United States, is:—

1. A combined grid lead and clamp for 110

high power discharge devices comprising a metallic sleeve adapted to embrace a portion of an envelop, a metallic strap secured to the sleeve, said strap comprising a flexible strip member which terminates in a grid lead, said strip member extending in a direction substantially parallel to the outer surface of the sleeve.

2. In a large power thermionic apparatus, a combined grid lead and clamp comprising a cylindrical metallic sleeve adapted to embrace a cylindrical protuberance projecting

from the surface of an envelop, a metallic strap detachably secured to the sleeve, said strap comprising a flexible conductor of 15 large current-carrying cross-sectional area and extending in a direction substantially concentric with respect to the outer circumference of the sleeve and a grid lead adapted to be secured to the end of the conductor 20 remote from the strap.

In witness whereof, I have hereto set my hand this 17th day of August, 1926.

WILLIAM A. RUGGLES.
